US0D1084175S

(12) **United States Design Patent** (10) **Patent No.:** **US D1,084,175 S**
(45) **Date of Patent:** **** Jul. 15, 2025**

(54) **REBOUND NET**

(71) Applicant: **Luping Liu**, Shenzhen (CN)

(72) Inventor: **Luping Liu**, Shenzhen (CN)

(**) Term: **15 Years**

(21) Appl. No.: **29/979,408**

(22) Filed: **Dec. 18, 2024**

(51) **LOC (15) Cl.** **21-02**

(52) **U.S. Cl.**

USPC **D21/705**

(58) **Field of Classification Search**

USPC D21/305, 698, 699, 704, 705, 721, 722,
D21/784

CPC ... A63B 69/00; A63B 69/0097; A63B 63/004;
A63B 63/00

(57) **CLAIM**

The ornamental design for a rebound net, as shown and described.

DESCRIPTION

FIG. 1 is a front perspective view of a rebound net, showing my new design;

FIG. 2 is another front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view showing my design in an altered configuration;

FIG. 10 is a front perspective view showing my design in an altered configuration;

FIG. 11 is a side view showing my design in an altered configuration; and,

FIG. 12 is a side view showing my design in another altered configuration.

1 Claim, 12 Drawing Sheets
